UNITED STATES PATENT OFFICE.

JULIUS F. GRAESSLE, OF FOND DU LAC, WISCONSIN.

METAL FEEDER FOR TYPE-CASTING MACHINES.

Application filed February 5, 1921. Serial No. 442,722.

To all whom it may concern:

Be it known that I, JULIUS F. GRAESSLE, a citizen of the United States, residing at Fond du Lac, in the county of Fond du Lac and State of Wisconsin, have invented new and useful Improvements in Metal Feeders for Type-Casting Machines, of which the following is a specification.

This invention relates to type casting machines and more particularly to means for feeding metal to the metal pot of such a machine.

An object of the invention is to provide a mechanism for automatically feeding metal to the metal pot of a type casting machine which is automatically operated by the operation of the type casting-machine and the operation of which is controlled by the level of the molten metal in the metal pot.

Another object of this invention is to provide a metal feeding mechanism as specified which requires no attention when once it is adjusted, does not require an extra burner, feeds metal to the pot only when the machine is in operation and then only at such times as the level of the molten metal in the pot falls below the desired point, and one which, owing to its manner of feeding the metal, permits the maintaining of an even temperature of the metal in the pot at all times producing solid slugs with clear faces.

Other objects of the invention are to provide a metal feeding mechanism as specified which is simple in construction, easily accessible, does not in any way interfere with the automatic stopping of the pawls or any of the delicate working parts of metal casting machines and one which can be recharged when necessary in a very short time and with the minimum amount of work.

Other objects will appear in the following detailed description and in the accompanying drawings wherein:

Fig. 1 is a side elevation of the improved metal feeding mechanism.

Fig. 2 is a front elevation of the improved feeding mechanism.

Fig. 3 is a detailed perspective of a clamp used in attaching the metal feeding mechanism to a type casting machine.

Referring more particularly to the drawing, the improved metal feeding mechanism illustrated is particularly designed for use

in connection with a "linotype" machine, however, it is to be understood that it may be used with any analogous type of type casting machine. The metal feeding mechanism comprises a frame 1 which is designed for attachment to a type casting machine by a suitable clamp structure 2, as shown in Fig. 2 of the drawings, and by means of the bracing arm 3 so as to permit attachment of the metal feeding mechanism to the type casting machine without requiring the drilling of holes in the machine.

A shaft 5 is rotatably supported by the supporting structure 1 and has a flexible member 6 connected thereto, which flexible member may be either a chain, cable, or the like, the flexible member 6 passes upward from the shaft 5 about a sheave pulley 7 carried by the rod 8 at the top of the frame 1 and over a second sheave 9 rotatably mounted upon a rod 10, which is supported at the top of the frame 1 outwardly from the sheave 7. A metal carrying hook 11 is connected to the free end of the flexible member 6, preferably by a swivel 12 and this hook is adapted to engage through the eye 13 in a bar or pig 14 of type metal. In practical use this bar or pig 14 of metal is relatively long and weighs approximately 30 to 35 pounds so as to provide metal sufficient for a relatively long time of operation of the type casting machine making it necessary to recharge the metal feeding mechanism only at relatively long intervals, thereby allowing the operator uninterrupted work at the keyboard and making it unnecessary for him to look into the metal pot every few minutes to determine the level of the molten metal therein and to replenish the supply as in the ordinary machine when the metal is fed into the pot manually by the operator.

The shaft 5 has an escapement disc 15 rotatably mounted thereon and connected to the shaft for rotation therewith by a pawl 16 which engages a pin 17 extending diametrically through the shaft. A spring 18 is provided to maintain the pawl 16 in engagement with the pin 17. The escapement disc 15 has a plurality of laterally extending, circumferentially spaced pins 19 attached thereto at predetermined intervals about a circle concentric of the axis of the disc. An escapement lever 20 is provided for coac-

tion with the pins 19 and this escapement lever 20 is carried by the escapement shaft 21 and has a pin 22 on its free end which engages against one of the pins 19 for holding the escapement disc 15 against rotation under the weight of the metal bar or pig 14 and consequently prevent the unwinding action of the flexible member 6 from the shaft 5 and also prevent the feeding of metal bar into the metal pot 23 of a type casting machine. A lever arm 24 is attached to the escapement shaft 21 and has a spring 25 connected thereto which urges and normally holds the pin 22 in engagement with one of the lateral studs or pins 19. An operating lever 26 is connected to the escapement shaft 21 and has an arm 27 connected thereto. The arm 27 is in turn connected to a lever 28 pivoted, as shown at 29, to the base 30 of the frame 1 and carrying a plate 31. The plate 31 has a lateral projection 32 on its lower end which is positioned in the path of a stud 33 carried by the first elevator cam of a "linotype" machine as indicated at 34. When the stud 33 engages the plate or bracket 31, the rotation of the cam 34 will rock the lever 28, which in turn operates the escapement mechanism to move the pin 22 out of engagement with the pin 19 permitting the escapement disc 15, and consequently the shaft 5, to rotate one step in its complete revolution.

The operation of the escapement mechanism is relatively quick so that the pin 22 will be out of the path of the pins 19 only long enough to permit the pin 19 with which it has been in engagement, to pass the normal position of the pin 22 after which the spring 25 will act to move the pin 22 into position in engagement with the next subsequent pin 19 on the disc 15 thereby permitting only a predetermined step movement of the escapement mechanism and of the metal pig 14 into the metal pot 23.

However, it is not necessary to feed metal into the metal pot 23 every time the cam 34 makes a complete rotation and consequently operates the lever 28, therefore, to prevent excessive feeding of metal into the pot, means, preferably by the variation of the level of the molten metal in the metal pot 23, has been provided for controlling the feeding of the metal pig 14.

The control mechanism adjustment includes a brake band 35 mounted about the perimeter of the escapement disc 15. The brake band 35 is preferably lined with a band 36 of friction material such as leather or the like to permit firm braking action of the brake band upon the disc 15. One end of the brake band 35 is connected to the supporting frame 1 while the other end is connected to a pin 37. The pin 37 is in turn connected to a brake lever 38, the amplitude

of movement of which is limited by an adjustable stop screw 39.

A lever 40 is provided for operating the brake lever 38 and the amplitude of movement of this lever 40 is regulated by adjustment of an adjustable stop screw 41. A plate 42 is carried by the lever 40 and rides upon the molten metal as indicated at 43 in the metal pot 23 and when the metal is at its normal elevation the float is held in position to maintain the brake band 35 in braking engagement with the perimeter of the disc 15 to prevent rotation of this disc when the pin 22 is moved out of engagement with a pin 19. As the elevation of the molten metal in the metal pot 23 lowers the float moves downwardly therewith and unlocks the lever 40 for releasing the brake 35 to permit the disc 15 to rotate and allow feeding of the metal pig 14 into the metal pot 23 and this feeding operation is continued in step by step formation at predetermined intervals upon the movement of the pin 22 out of engagement with the respective pins 19 until the molten metal in the pot 23 has reached is normal or desired level.

A hand crank 47 is mounted on the shaft 5 and when it is desired to place a new metal pig or bar 14 upon the hook 11, the pawl 16 is released from engagement with the pin 17 and the shaft 5 is manually rotated to wind the flexible member 6 thereon and draw the hook 11 upwardly to its starting or initial position.

It is, of course, to be understood that the invention may be constructed in various other manners and the parts associated in different relations and, therefore, I do not desire to be limited in any manner except as set forth in the claims hereunto appended.

Having thus described my invention what I claim is:

1. In a metal feeding mechanism, a feeding shaft, an escapement disc rotatable thereon, a spring actuated pawl pivotally carried by said escapement disc, means on said shaft engaged by said pawl for connecting the disc to the shaft, an escapement mechanism including a lever arm, an escapement lever operated by said arm, a pin carried by said escapement lever for cooperation with said escapement disc to control rotation of the disc, a brake band about said escapement disc, a lever for moving said brake band into and out of braking position, and a float operated lever for controlling operation of said brake band operating lever.

2. In a metal feeding mechanism, a feeding shaft, an escapement disc rotatable thereon, a spring actuated pawl pivotally carried by said escapement disc, means on said shaft engaged by said pawl for connecting the disc to the shaft, an escapement mechanism including a lever arm, an es-

capement lever operated by said arm, a pin carried by said escapement lever for cooperation with said escapement disc to control rotation of the disc, a brake band about said escapement disc, a lever for moving said brake band into and out of braking position, a float operated lever for controlling opera-

tion of said brake band operating lever, and means connecting said brake operating lever and float operated lever whereby the relative 10 amplitude of movement of the levers may be regulated.

In testimony whereof I affix my signature.

JULIUS F. GRAESSLE.
